UNITED STATES PATENT OFFICE.

KIRTLAND C. GARDNER, OF PITTSBURG, PENNSYLVANIA, ASSIGNOR OF ONE-HALF TO UNITED ENGINEERING & FOUNDRY COMPANY, OF PITTSBURG, PENNSYLVANIA, A CORPORATION OF PENNSYLVANIA.

TRANSFER SYSTEM.

No. 879,131.

Specification of Letters Patent.

Patented Feb. 11, 1908.

Application filed April 4, 1907. Serial No. 366,375.

To all whom it may concern:

Be it known that I, KIRTLAND C. GARDNER, of Pittsburgh, Allegheny county, Pennsylvania, have invented a new and useful Transfer System, of which the following is a full, clear, and exact description, reference being had to the accompanying drawings, forming part of this specification, in which—

Figure 1 is a cross-section, showing one form of apparatus embodying my invention. Fig. 2 is a partial plan view of the same. Fig. 3 is an enlarged plan view of the guide and tilting doors in the delivery portion thereof; Fig. 4 is a cross section of the guide and chain, on the line IV—IV of Fig. 3; Figs. 5 and 6 are detail views of the chain and dog which I preferably employ, and Fig. 7 is an enlarged section of the lower runway or track, taken on the line VII—VII of Fig. 1.

My invention relates to the side transferring of metal in steel mills; and more especially to the side transfer of metal being rolled from one pass to another pass located at the side thereof, and either at the same or a different level. The apparatus may also be applied to hot bed practice or to the side transfer of metal on supports, whether grouped or not.

In the drawings, in which I show my invention as applied to the side transfer of metal from one roller table in line with the rolling mill pass to another roller table at a higher level, and arranged to feed the metal to another pass; 2 indicates the rollers of one table which are shown as plain faced, and 3 the parallel rollers of another roller table, which in this case are shown as provided with circumferential grooves. These rollers may be driven or not as desired; and I have shown them as positively driven through the usual longitudinal shafts 4 and 5, having bevel gear connections 6 and 7 with the shafts of the table rollers.

At desirable intervals apart I provide the upper guide-ways for the sprocket chains 8, these guideways preferably consisting of two channel shaped sections with wider lower flanges, the flanges projecting toward each other. These channels may be secured to and supported upon the side I-beam members 9 of the roller tables, and preferably terminate in bell-shaped cast sections 10 at each end. The intermediate portion of the guide-way extends upwardly at an angle, as shown in Fig. 1, to transfer the metal from

one level to the other level during its side movement.

The sprocket chains engage sprocket wheels 11 and 12, mounted on shafts 13 and 14 outside the roller tables, the shaft 13 adjacent to the delivery table being driven by any suitable connections, so as to exert a pull on the upper portion of the chain. The chain, in its lower path, is supported upon a longitudinal guide 15, and the shaft 14 may be provided with adjusting devices to regulate the tension on the chains.

The chains may be of any desirable form, but are preferably constructed as shown in Figs. 5 and 6, two links alternating with one link; and rollers 8' being employed to carry the chains, the rollers traveling between the flanges 8^a of the flanged beams 8^b. The lower flanges form tracks for the rollers, and the upper ones serve to hold the chains down to their proper plane of movement. I preferably employ two of the dogs 16 with the apparatus shown, each dog being in the form of a bell-crank pivoted to the chain-pin between two of the links, and being of U-shape with its lower legs straddling the links and connected by a cross-bar below them. This prevents the dog from being swung forwardly beyond its upright position, while the two lower legs rest upon the inner flanges of the channel track which hold it in upright position, except where these flanges are cut away to deposit the metal. In the form shown, the track through its delivery portion between the rollers 3 is cut away in its bottom, and the bottom is made in separate sections 9 or doors 17, carried on brackets 17^a extending around the guide-way and pinned or otherwise secured each to a separate rock shaft 18, which is capable of endwise movement in its bearings 18'. In the form shown, the rollers 3 are adapted to feed three passes, and the guide-way bottom is preferably made in three parts, any one of which may be dropped to allow dropping of the dog at this point. The bottom sections or doors are held elevated or closed by lugs 19, which rest upon ledges or projections 19^a (see Fig. 4). To release and drop any door, the corresponding shaft 18 is rocked to raise the lug 19 off from the shelf 19^a. Said shaft is then moved endwise a short distance, sufficient to cause the lug 19 to clear the end of the shelf 19^a, when the door falls by gravity to the position

shown in full lines at the right hand side of Fig. 4.

In the operation of the apparatus the chain mechanism is normally still. When 5 a metal section is delivered on the rollers 2, the operator starts the shaft 13 into motion and the chain dogs entering the left-hand bell mouths of the guides are supported on the guide-way to prevent their backward 10 tilting. In the continued travel of the chains these dogs push the metal which slides on the top of their channel guide-ways, until the dogs reach the lower floor-sections of the guide at the table 3, when the dogs being no 15 longer supported, will swing backwardly into the position shown at the upper right-hand of Fig. 1, thus leaving the metal at the desired point. The travel of the chains may then be stopped by the operator, and when 20 the next section arrives on the roller-table 2 he will again start the chains into motion, when the next dog will act in the same manner.

The advantages of the invention will be 25 apparent to those skilled in the art. The use of the chains with swinging dogs enables us to stop the metal at any desired point in the side transfer and without the use of complicated mechanism. The floor or bottom 30 sections of the guide may be cut out or dropped at any desired point or points where the metal is to be stopped or temporarily detained; the sections may be grouped between the two tables, if desired, and the dogs used 35 to feed to one side of the group and take away from the other side, and again leave at the roller table, or not, as desired. Either or both of these operations may be carried out by simply providing the removable floor 40 sections or dog supports where it may be desired to stop the metal; or by cutting away these dog supports if no adjustment is desired in this regard. The operations are easily and quickly carried out, and the apparatus 45 is not liable to get out of order. The chain guides serve as skids or supports for the metal in its sidewise movement, and prevent jumping upward of the chain in the upper path of its travel.

50 Any number of dogs may be employed; the shape and arrangement of the dogs may be varied, as well as the dog supports or means for holding the dogs elevated; the upper path

of the chains may extend on the same level, or may change level; the device may be employed for hot beds or other side transfer apparatus; and other changes may be made without departing from my invention. 55

I claim:

1. In metal transfer apparatus, a continuous flexible carrier, dog pivoted thereto, means for normally holding the dog in its operative position, and means at different points in the path of movement of the dog whereby it may be caused to swing at any one 60 of said points to stop the metal; substantially as described.

2. In metal transfer apparatus, a carrier chain, a dog pivoted thereon, means for normally holding the dog in its operative position, and means at different points in the path of movement of the dog whereby it may be caused to swing at any one of said points to stop the metal, substantially as described. 70

3. In metal transfer apparatus, a chain, a dog pivoted thereon, and a dog-support having removable sections arranged to change the point where the dog tilts to release the metal; substantially as described. 75

4. In metal transfer mechanism, a continuous chain having dogs pivoted thereto, hinged supports for the dogs at different points in the travel of the chain, and means for dropping any one of said supports to cause the dogs to tilt; substantially as described. 80

5. In metal transfer mechanism, a continuous carrier chain having dogs pivoted thereto, a bottom support for said dogs having hinged sections or doors, supports for said sections or doors, and means for disengaging 90 the sections or doors from their supports; substantially as described.

6. In metal transfer mechanism, a continuous carrier chain having dogs pivoted thereto, a bottom support for said dogs having hinged sections or doors, supports for said sections or doors, and endwise movable rock 95 shafts carrying the sections or doors, substantially as described.

In testimony whereof I have hereunto set 100 my hand.

KIRTLAND C. GARDNER.
